UNITED STATES PATENT OFFICE

CHARLES J. RICHTER, OF BERWYN, ILLINOIS; ASSIGNOR TO THE GOSS PRINTING PRESS CO., OF CHICAGO, ILLINOIS, A CORPORATION OF ILLINOIS

DELIVERY APPARATUS FOR PRINTING PRESSES

Application filed September 10, 1928. Serial No. 305,022.

My invention relates to delivery apparatus for printing presses of the type arranged for separating into unit piles the newspapers coming from a press as the completed papers are taken from the folder and placed one at a time by a fly or other suitable device upon a delivery belt or other receiver. It is the object of my invention to provide in an apparatus of this type an improved form and arrangement of parts adapted to act upon the series of papers at predetermined intervals in the operation of the press for causing one or more of such papers to assume a changed position on the receiver as compared with the position of the remaining papers whereby the papers on the receiver are divided into unit bunches.

In devices of this type in use heretofore, guides or deflectors movable into the path of the papers have been employed, the arrangement being such that one of the papers at intervals is brought into engagement with the guide or deflector which obstructs the normal path of the paper and causes the paper to move more or less independently of the usual delivery mechanism into position on the receiver. In some cases in the use of mechanism of this type, the movable guide when moved into the path of the papers merely deflects the engaged paper so as to cause such paper to move along the face of said movable guide instead of along the face of the stationary guide. In other cases, the guide or deflector interrupts the forward movement of the paper and is then withdrawn, leaving the paper to fall substantially without any control or guiding. In either case, the paper is diverted from the usual controlling means and no adequate controlling means is substituted of a type adapted to have anything like positive action with respect to the movement of the paper.

It is one of the objects of my invention to provide improved means for displacing the critical papers forwardly on the receiver for indicating the division into unit piles whereby the movement of the paper into changed position is more completely controlled by positively acting means and whereby such displaced paper or papers are held positively

against backward movement into the normal position on the receiver. To this end, it is one of the objects of my invention to provide a construction comprising means movable downwardly with the paper and maintained in position until such displaced paper is held in position by the weight of other papers deposited above it on the receiver.

It is another object of my invention to provide an improved form of contact means for bringing about the changed position of the papers at intervals whereby such contact means may serve to support the paper from beneath as well as to engage the edge of the paper so that the action of said contact means shall be more completely positive; and whereby the engaged paper may be held in continued engagement with said contact means at the same point on the contact means throughout the movement of the paper downwardly into position on the receiver, means being provided for preventing normally any shifting of the paper with respect to the contact means during such downward movement of the paper.

It is another object of my invention to improve devices of this type in sundry details hereinafter pointed out. The preferred means by which I have accomplished my several objects are illustrated in the accompanying drawings and are hereinafter specifically described. That which I believe to be new and desire to cover by Letters Patent is set forth in the claims.

In the drawings,

Fig. 1 is an end view of the preferred form of my improved delivery apparatus in position below the creasing rollers of the folding apparatus, the same being illustrated more or less diagrammatically;

Fig. 2 is a view of the parts shown in Fig. 1 as seen from the right in said figure; and

Figs. 3, 4, 5 and 6 are views on a smaller scale similar to Fig. 1 but showing changed positions of the parts.

Referring to the several figures of the drawing, in which corresponding parts are indicated by the same reference characters, 10 and 11 indicate folding rolls of any approved type revolvably mounted in operative

relation to each other upon a frame-work not shown, such rolls being in such position with respect to a printing press as to receive a series of papers downwardly therebetween. 5 Guide bars 12 of usual type are mounted in position below the folding rolls 10 and 11, with the upper end portions of such guide bars extending into grooves 13 formed in the face of the folding roller 11 in the usual manner so as to permit the papers passing between the folding rollers to pass downwardly along the faces of such guide bars. A delivery apparatus of approved type, comprising in the form shown three rotary fly devices 14, 10 is mounted a short distance from the rear face of the guide bars 12. Each of the guide bars 12 is provided with a diagonally disposed portion, as indicated at 15 in Fig. 1, such diagonally disposed portion being substantially 15 in the form of an arc about the axis upon which the fly devices 14 rotate. In the normal operation of the apparatus, the papers passing downwardly between the folding rollers 10 and 11 are received in the pockets provided by the arms 16 of the fly device and are caused to move downwardly along the faces of the guide bars so as to be deposited in order upon a series of belts 17. The fly devices 14 are rotated in counter-clockwise 20 direction in Fig. 1 in timed relation to the movement of the papers between the rollers 10 and 11 for effecting this result, as is well understood in the art.

A plurality of the belts 17 are provided 25 mounted at their rear ends upon pulleys or sheaves 18 which are driven slowly for carrying the upper plies of the belts toward the left in said Fig. 1 for causing the papers to be distributed in regularly spaced relation 30 upon the belts under normal conditions.

For causing one of the papers at timed intervals to assume a changed position upon the belts 17 as compared with the position of the remaining papers thereon, I have provided 35 a plurality of stop arms 19 which are normally held in position above the diagonally disposed portions of the guide bars 12, as is indicated in Fig. 1, but which are movable downwardly beyond the guide bars into the path of the papers at the desired intervals for causing a changed position of one of the papers. The forward ends of the arms 19 are notched so as readily to receive the lead edge 40 of the paper in the angle of the notch, with the lower finger of the notch in such position in substantial alignment with the arm as to provide a support for the paper from underneath as well as to stop the forward movement 45 of the paper. By the provision of the angularly arranged fingers forming the notch, a paper engaging the notch from above is held in position and the lead edge of the paper is prevented from shifting in position 50 with respect to the arm during the downward

movement of the arm and paper together for the deposit of the paper upon the receiver.

For providing the desired movement of the stop arms 19, such arms are slidably mounted in slide boxes 20 which in turn are mounted upon a rock shaft 21 so as to swing vertically thereabout under control of the rock shaft. The means for controlling the position of the rock shaft 21 and for controlling thus the angular position of the slide boxes 20 and the stop arms 19 comprises an arm 22 carried by said shaft at one end portion thereof, being provided with a roller 23 which engages a cam 24 mounted upon a drive shaft 25, such shaft 25 being the shaft 70 upon which the sheaves 18 are supported as above described. The shaft 25 is to be driven in timed relation to the papers advancing between the rollers 10 and 11, in the construction shown the shaft 25 being given a single 75 complete rotation for each fifty papers passing between the rollers 10 and 11 to the delivery apparatus.

For controlling the longitudinal position of the slidably mounted stop arms 19 with respect to the slide boxes 20, I have provided links 26 pivotally connected at their upper ends with the stop arms and pivotally connected at their lower ends with arms 27 arising from the rock shaft 28 which is pivotally mounted in any suitable bearings in the frame of the machine. The position of the rock shaft 28 is controlled by a cam 29 non-rotatably mounted with respect to the shaft 25, such cam acting upon the shaft 28 through 90 the medium of a roller 30 carried by an arm 31 mounted upon the shaft 28, such roller engaging the face of the cam 29.

With the parts in the position as illustrated in Fig. 1, and with the fly devices 14 and the shaft 25 and its driven parts rotating in counter-clockwise direction in said Fig. 1, the stop arms 19 are held out of the path of the papers passing along the face of the guide bars 12. A very short time thereafter, the parts will have assumed the position shown in Fig. 3, with the roller 23 in contact with the step 32 of the cam 24, the step 32 being located in such position as to cause the stop arm 19 to stand in position immediately below the upper end of the diagonally disposed portion 15 of the guide bar 12 in such position that the downwardly moving paper which has shortly before entered one of the pockets of the fly device engages the notched forward end of the stop arm from above so as to be at least partially supported by said arm. When the paper reaches its normal engaging position at the angle of the notch in the stop arm, such paper is under the control of the arm so that upon subsequent downward movement of the arm the paper is led along the prescribed path to a definite predetermined position on the receiver different from that at which the adjacent preceding 100 105 110 115 120 125 130

paper was deposited on the receiver. In the construction illustrated, such downward movement of the arm with the paper is brought about by reason of the passage of the roller 23 from the step 32 to the step 33 of the cam face due to the continued rotation of the cam in counter-clockwise direction as shown in Fig. 4.

Following the movement of the parts to the position shown in Fig. 4, with a paper being held in changed position upon the belt 17 as compared to the position taken by the next preceding papers thereon, the delivery of the papers downwardly continues, the following papers being piled on the arms 19 adjacent to the guide bars 12 and extending partially over the top face of the displaced paper so as to weight it down and prevent its movement with respect to the adjacent papers. After one or more papers have been deposited on top of the displaced paper so as to render further presence of the arms adjacent to the receiver unnecessary, the arms are slowly withdrawn by a movement backwardly underneath the papers piled thereon so as to deposit such accumulated papers on the receiver. Such movement of the arms is effected by the engagement of the roller 30 with a rise of the cam 29 for moving the arm 27 toward the right in said Fig. 4, serving to move the stop arm 19 gradually from the position shown in Fig. 4 to the retracted position as shown in Fig. 5. Shortly after the parts have assumed the position shown in Fig. 5, the roller 23 controlling the position of the shaft 21 engages the rise 34 of the cam 24 causing the slide boxes 20 and the stop arms 19 to be swung about the shaft 21 into the position as shown in Fig. 6, which corresponds with the angular position of the boxes and the stop arms as shown in Fig. 1. Shortly thereafter, the roller 30 passes out of engagement with the rise of the cam 29, permitting a spring 27^a as shown in Fig. 1 to swing the arm 27 toward the left in Fig. 6 again to the position as shown in Fig. 1, and causing the stop arms 19 to reassume the position as shown in Fig. 1.

From the above description, it will be seen that normally the stop arm stands in the position shown in Fig. 1; that at a predetermined time in the rotation of the cam 24 the stop arm swings downwardly to the position shown in Fig. 3 where it serves by contact with the forward edge of a paper to stop the downward movement of such paper; that immediately thereafter the stop arm with the paper in position in the notched forward end thereof swings downwardly into the position shown in Fig. 4 in advance of the normal position of the paper on the belt 17; that after one or more papers have been deposited subsequently on top of the paper in abnormal position the stop arm 19 is retracted by longitudinal movement substantially par-

allel to the faces of the belts; that after the stop arm assumes the position shown in Fig. 5, the stop arm and slide box are swung upwardly to the position shown in Fig. 6, after which the stop arm is again moved forward to the position shown in Fig. 1.

I have found the device as shown in the drawings and as above described very satisfactory in operation. The movement of the stop arm downwardly with the paper serves to control the movement of the paper so as to insure the positioning of the paper at the desired point upon the belts 17. The retention of the stop arms 19 in their advanced position until one or more subsequently delivered papers are deposited on top of the changed position paper serves to insure that the position of the papers shall be changed very little if any at all by the withdrawal of the stop arms backwardly along the face of the belt.

As is clearly shown in Fig. 1, the opposite sides of the cam 24 are formed similarly. That is to say, at each side thereof the cam 24 is provided with a step 32, a still lower step 33 and a rise 34. Such arrangement is provided for use in case it is desired to divide the papers into unit piles of 25 rather than unit piles of 50. For the normal operation of the device as first above described, a shield 35 pivotally mounted upon a pin 36 is provided in connection with the cam 24, adapted when held in normal position as shown in said Fig. 1 to cover the edge of the cam at one side thereof so as to make one set of cam steps ineffective, being held in such position by means of a bolt 36. When it is desired to employ the cam steps at both sides of the cam, the bolt 37 is removed and replaced in an opening 38 in the cam, the bolt serving in such position to hold the shield 35 away from the operative edge portion of the cam.

While I prefer to employ a construction substantially as shown in my drawings and as above described, it is to be understood that my invention is not limited to that particular form except so far as the claims are so limited by the prior art, it being understood that changes may well be made in the construction shown without departing from the spirit of my invention.

I claim:

1. In a delivery apparatus for papers moving downwardly in timed relation, the combination of a receiver to which said papers are delivered, and means movable into the normal path of the papers adapted by continued engagement with one of said papers at intervals as it moves downwardly to said receiver to lead said paper to a different position on said receiver from that at which the adjacent preceding papers are deposited thereon.
2. In a delivery apparatus for papers moving downwardly in timed relation, the com-

5 bination of a receiver to which said papers are delivered, and means adapted by movement into the normal path of the papers to engage one of said papers at intervals and adapted by movement downwardly with said paper in continued engagement therewith to direct the paper to changed position on said receiver as compared with that at which the adjacent preceding papers are deposited thereon.

10 3. In a delivery apparatus for papers moving downwardly in timed relation, the combination of a receiver to which said papers are delivered, and means having an upwardly open mouth adapted by movement into the normal path of the papers to engage the lead edge of one of said downwardly moving papers at intervals and adapted by movement downwardly while supporting said paper from below to direct the paper into changed position on said receiver as compared with that at which the adjacent preceding papers are deposited thereon.

15 4. In a delivery apparatus for papers moving downwardly in timed relation, the combination of a receiver to which said papers are delivered, and means movable into the normal path of the papers adapted by engagement with one of said papers at intervals to provide at least a partial support for said paper and to lead it to changed position on said receiver as compared with that at which the adjacent preceding papers are deposited thereon.

20 5. In a delivery apparatus for papers moving downwardly in timed relation, the combination of a receiver to which said papers are delivered, and a notched member movable into the normal path of the downwardly moving papers adapted by downward movement in continued engagement with one of said papers at intervals to direct said paper to a changed position on said receiver as compared with that at which the adjacent preceding papers are deposited thereon and adapted by further continued engagement with the paper to prevent it from moving backwardly on said receiver.

25 6. In a delivery apparatus for papers moving downwardly in timed relation, the combination of a receiver to which said papers are delivered, and a notched swingingly mounted arm movable for bringing the notch into the normal path of said papers at intervals adapted by engagement of one of said papers with said notch to direct the lead edge of said paper into changed position on said receiver as compared with that at which the lead edges of the adjacent preceding papers are deposited thereon.

30 7. In a delivery apparatus for papers moving downwardly in timed relation, the combination of a receiver to which said papers are delivered, and a swingingly mounted arm having an upwardly open notch therein mov-

able into the normal path of said papers at intervals adapted by engagement of one of said papers in said notch at least partially to support said paper and to direct the paper into changed position on said receiver as compared with that at which the adjacent preceding papers are deposited thereon. 70

8. In a delivery apparatus for papers moving downwardly successively in timed relation to each other, the combination of a receiver, means normally acting on said papers successively as they pass serving to deposit the papers in regularly piled arrangement on said receiver, a stop movably mounted adjacent to the path of said papers, means controlling the position of said stop for holding it normally out of the path of said papers and for causing the stop at timed intervals to move downwardly into position to engage one of said papers and then to move downwardly with said paper serving to deposit the paper in changed position upon said receiver as compared with the position at which the other papers are deposited thereon, and means for withdrawing the stop by a movement substantially parallel with the plane of the receiver. 75 80 85

9. In a delivery apparatus for papers moving downwardly successively in timed relation, the combination of a belt, means for moving said belt forwardly, a rotary fly device to which said papers pass as they move downwardly adapted normally to deposit the papers in regularly overlapping position on said belt, a stop movably mounted adjacent to said rotary fly device, means controlling the position of said stop for holding it normally out of the path of said papers and for causing the stop at timed intervals to move downwardly into position to engage one of said papers and then to move downwardly with said paper serving to deposit the paper in advanced position upon said belt as compared with the position at which the other papers are deposited thereon, and means for withdrawing the stop by a movement longitudinally of the belt. 90 95 100 105 110

10. In a delivery apparatus for papers moving downwardly successively in timed relation, the combination of a receiver, means serving normally to deposit the papers in regularly piled arrangement on said receiver, a stop arm swingingly mounted above said receiver, means for controlling the angular position of said arm for holding it normally out of the path of said papers and for causing the arm at timed intervals to swing downwardly into position to engage one of said papers and to swing downwardly with said paper serving to deposit the paper in changed position upon said receiver as compared with the position at which the other papers are deposited thereon, and means for giving the stop arm a longitudinal movement 115 120 125 130

for withdrawing it from engagement with said papers.

11. In a delivery apparatus for papers moving downwardly successively in timed relation, the combination of a receiver, means serving normally to deposit the papers in regularly piled arrangement on said receiver, a stop arm swingingly mounted above said receiver, means for controlling the angular position of said arm for holding it normally out of the path of said papers and for causing the arm at timed intervals to swing downwardly into position to engage one of said papers and to swing downwardly with said paper serving to deposit the paper in changed position upon said receiver as compared with the position at which the other papers are deposited thereon, means for withdrawing the stop arm by a movement substantially parallel with the receiver, means for swinging the stop arm again to its raised angular position, and means for giving said stop arm a reverse movement along the receiver for bringing it again to its normal position ready for another operation.

12. In a delivery apparatus for papers moving downwardly in timed relation, the combination of a receiver, a guide bar, means for directing the papers normally along the face of said guide bar into regularly piled arrangement on said receiver, a stop movably mounted adjacent to said guide bar, and means for controlling the position of said stop adapted normally to hold the stop out of the path of said papers and adapted at timed intervals to cause said stop to move beyond the face of the guide bar for engaging one of said papers and then to move downwardly with said paper for depositing the paper in changed position upon said receiver as compared with the position at which the other papers are deposited thereon.

13. In a delivery apparatus for papers moving downwardly in timed relation, the combination of a receiver, means serving normally to deposit the papers in regularly piled arrangement on said receiver, stop means normally held out of the path of said papers and movable at timed intervals into engagement with the paper for causing such paper to take a changed position on said receiver as compared with that taken by the other papers, and means actuated in timed relation to the movement of said stop means adapted after at least one subsequently delivered paper has been piled on top of said paper in changed position to withdraw said stop means by a movement substantially parallel with the plane of the superposed paper so as to have substantially no tendency to disarrange the papers on said receiver.

14. In a delivery apparatus for papers moving downwardly in timed relation, the combination of a receiver to which said papers are delivered, swingingly mounted arms, means

for holding said arms normally out of the path of said papers and for swinging said arms temporarily into position adjacent to said receiver at intervals for receiving and supporting a plurality of the papers out of engagement with the receiver, and means for withdrawing said arms from the position adjacent to the receiver by a movement substantially parallel with said receiver.

15. In a delivery apparatus for papers moving downwardly in timed relation, the combination of a receiver to which said papers are delivered, swingingly mounted arms, means for holding said arms normally out of the path of said papers and for swinging said arms temporarily into position adjacent to said receiver at intervals for receiving and supporting a plurality of the papers out of engagement with the receiver, and means for withdrawing the arms from their position adjacent to said receiver by a movement longitudinally of the arms backwardly along the face of the receiver.

16. In a delivery apparatus for papers moving downwardly successively in timed relation, the combination of a receiver, means serving normally to deposit the papers in regularly piled arrangement on said receiver, a stop arm swingingly mounted above said receiver, and cam means for controlling the angular position of said stop arm, serving in one position to hold the arm above the path of the papers, serving in another position to hold the arm in slightly lowered position so as to engage one of said papers, and serving by movement to another position to cause said stop arm to move downwardly with said engaged paper for depositing the paper upon said receiver in changed position as compared with that at which the other papers are deposited on said receiver.

17. In a delivery apparatus for papers moving downwardly successively in timed relation, the combination of a receiver, means serving normally to deposit the papers in regularly piled arrangement on said receiver, a pivotally mounted slide box, a stop arm slidably mounted in said slide box and projecting when in extended position into close proximity to the path of movement of said papers, means for controlling the angular position of said slide box for holding the stop arm out of the path of the papers and for causing the stop arm at timed intervals to move downwardly into position to engage one of said papers and then to move downwardly with said paper serving to deposit the paper in changed position upon said receiver as compared with the position at which the other papers are deposited thereon, and means for giving said stop arm a sliding movement in said slide box for withdrawing the arm from engagement with said papers.

18. In a delivery apparatus for papers moving downwardly successively in timed re-

lation, the combination of a receiver, means serving normally to deposit the papers in regularly piled arrangement on said receiver, a pivotally mounted slide box, a stop arm slidably mounted in said slide box and projecting when in extended position into close proximity to the path of movement of said papers, means for controlling the angular position of said slide box for holding the stop arm out of the path of the papers and for causing the stop arm at timed intervals to move downwardly into position to engage one of said papers and then to move downwardly with said paper serving to deposit the paper in changed position upon said receiver as compared with the position at which the other papers are deposited thereon, an arm swingingly mounted below said slide box, a link pivotally connected at one end with said swingingly mounted arm and at its other end with said slidably mounted stop arm, and means for giving said swingingly mounted arm a swinging movement for carrying the stop arm out of engagement with the papers on said receiver.

19. In a delivery apparatus for papers moving downwardly successively in timed relation, the combination of a receiver, means serving normally to deposit the papers in regularly piled arrangement on said receiver, a pivotally mounted slide box, a stop arm slidably mounted in said slide box and projecting when in extended position into close proximity to the path of movement of said papers, cam means serving in one position to hold the slide box in such angular position as to hold the stop arm above the path of the papers, serving in another position to hold said slide box in such angular position as to cause the stop arm to stand in slightly lowered position for engaging one of said papers, and serving by rotation from such position to cause the stop arm to swing downwardly with the slide box and to carry the paper downwardly into changed position on said receiver as compared with the position at which the other papers are deposited thereon and thereafter to cause the slide box and stop arm to swing again to their raised angular position, and means for giving said stop arm a sliding movement in said slide box for withdrawing the arm from engagement with said papers while the stop arm is in its lowered position and then for giving the stop arm a reverse sliding movement again into normal position above the path of movement of the papers after the slide box has been given its upward swinging movement.

CHARLES J. RICHTER.
